GAS-HEATED LAUNDRY IRON

Frederik Vilhelm Brostrom, Kingston-on-Thames, England

Application April 24, 1935, Serial No. 18,054
In Great Britain May 1, 1934

3 Claims. (Cl. 158—23.1)

This invention relates to gas-heated laundry irons primarily for domestic use of the kind having a tubular burner disposed within a combustion chamber, the lower wall of which is constituted by the sole of the iron, the tubular burner being formed with a number of small apertures, having in some cases short burner or jet tubes secured therein, adapted to produce short flame jets for heating the said sole of the iron.

The invention has for its main object to provide an improved gas-heated iron of this kind which shall be highly efficient while being of simple and compact construction.

A further object of the invention is to provide improved thermostatic means for controlling the gas supply to such irons so that they may readily be maintained at the correct temperature for ironing purposes.

In order to utilize to the best advantage the manual labour and time of an operator employing a laundry iron heated by the combustion of gas supplied to a burner disposed within the iron, it is necessary that the operative surface of the iron be maintained at such a temperature that the maximum amount of moisture will be evaporated from the fabric being ironed at each stroke of the iron.

Most gas-heated irons of this kind however are such that the temperature of the operative surface drops so quickly when damp fabrics are being ironed that the ironing operation must be interrupted until the temperature again rises to a suitable value.

The difficulty hitherto has been to establish good combustion of a sufficient quantity of gas within the confined space of the combustion chamber of an ordinary gas-heated iron and a gas-heated iron of sufficient capacity for ironing damp fabrics has, therefore, been of comparatively large size and of clumsy construction.

Now the conditions for good combustion in the confined space of the combustion chamber of a gas-heated iron of the kind referred to are the admixture with the gas of as much primary air as possible, the supply of a very small surplus of secondary air to the combustion chamber and a rapid exhaustion of the products of combustion from the latter.

According to the present invention these conditions are ensured in a gas-heated laundry iron of the kind referred to by providing a chimney, preferably of substantial height, through which the products of combustion are adapted to be exhausted from the combustion chamber, re-

stricting the inlet of secondary air to said chamber and disposing the tubular burner in such relation to the secondary air inlet and the upper wall of the combustion chamber that said secondary air is caused to pass beneath the burner to the flame jets and is precluded from flowing directly from the inlet to the chimney.

The chimney induces a draught through the combustion chamber and this, due to the restricted supply of secondary air which is available, produces a slight degree of vacuum within the said chamber serving to increase the amount of primary air drawn in by the gas stream and admixed therewith. In this way the complete combustion of a considerably larger quantity of gas can be effected in the confined chamber available in a laundry iron of compact construction than has hitherto been possible.

In order to prevent the temperature of the operative surface of the iron from rising excessively when slightly damped or dry fabrics are being ironed or when the iron is temporarily placed upon a stand or rest, a thermostat device is preferably incorporated in the iron adjacent said operative surface and adapted to reduce the quantity of gas being supplied when the said surface has reached a predetermined temperature, which may be one of a number of temperatures to which the thermostat may be selectively set.

Two constructions of a gas-heated laundry iron in accordance with this invention are illustrated in the accompanying drawings, wherein:—

Fig. 1 is a longitudinal vertical section, partly in elevation, of one form of iron provided with a thermostat device,

Fig. 2 is a plan view of said iron with some parts removed or broken away,

Fig. 3 is a vertical section taken on the line 3—3 of Fig. 1,

Fig. 4 is a rear elevation of the iron with the handle supposed removed,

Fig. 5 is a fragmentary sectional side elevation of another form of iron without a thermostat device,

Fig. 6 is a sectional plan view thereof, taken substantially on the line 6—6 of Fig. 5, and

Fig. 7 is a fragmentary detail view, partly in section, showing gas supply control means.

Referring to Figs. 1 to 4, it will be seen that the iron shown comprises a sole 1, of the usual substantially triangular outline in plan view, formed with a peripheral upstanding flange 1a of small height and a central longitudinally extending raised portion or rib 2 commencing adjacent the rear end of the sole and terminating

short of the point or front end of the latter. It will be understood that the rib 2 may be a separate casting or the like suitably secured to the sole 1.

5 The raised portion or rib 2 is bored longitudinally to provide a passage 3 in the front end of which is screwed a plug 4 having an axial extension 5 over which is engaged one end of a tube 6 of which the other end is welded, brazed 10 or otherwise secured in an aperture formed in the bend of a burner pipe 7 of substantially horse-shoe shape having its ends flattened and slotted, as indicated at 7a, in Fig. 2, and detachably secured by means of screws 8 to the sole 1 adjacent the ends of the rear edge thereof.

A series of apertures 9 is formed in the underside of each limb of the burner pipe 7 at such points that the flame jets issuing therefrom are directed downwardly and inwardly, preferably 20 at an angle of 30° to the vertical, towards the upper surface of the sole 1, see Fig. 3.

The requisite mixture of gas and primary air flows to the burner pipe 7, from a mixing chamber disposed in the passage 3, by way of a conically 25 tapering bore 10 (Fig. 1) formed axially of the plug 4, a conically enlarging bore 10a formed axially of the extension 5, and the tube 6.

As will be seen from Fig. 1, the mixing chamber is constituted by the space comprised between 30 the conical wall of the bore 10 in the plug 4 and the front or outer surface of a gas nozzle 11 the rear edge of which is pressed against an annular shoulder formed in the bore 3 by means of the tightening up of the plug 4, the pressure being 35 transmitted through a tubular spacer 12 and a packing ring 13 both surrounding the front end of the nozzle, as shown. The rear edge of spacer 12 is tapered or bevelled off inwardly so that the pressure exerted thereby on the packing ring 13 40 serves to force this outwardly against the wall of the bore 3.

Gas is injected across the mixing chamber into the mouth of the bore 10 from a small aperture 14 forming the outlet from the nozzle 11 which, 45 as shown in Fig. 1, has a somewhat flared inlet leading to the cylindrical bore or passage 3.

The gas stream traversing the mixing chamber entrains and admixes primary air therewith, said air having access to the mixing chamber 50 through a lateral aperture 16 in the spacer 12 and attaining to said aperture through a vertical bore 17 formed in the raised portion or rib 2 on the sole 1. The aperture 16 is disposed so that the primary air passing therethrough is delivered 55 into the annular space surrounding the wall defining the bore 10 forwardly of the mouth of said bore, which arrangement ensures that the primary air will be entrained equally all round the gas jet, flowing over the edge of the wall referred to into the bore 10. This ensures that 60 there is no loss of velocity of the gas stream passing through the Venturi-like passage 10, 10a to the burner pipe 7, with a consequent prevention of "lighting-back" to the injector nozzle 11.

65 It is preferred to provide means for regulating, within limits, the amount of primary air entering the bore 17 and such means may comprise, as shown, a tubular plug 18 screwed in the upper end of the bore 17 and formed with an enlarged laterally apertured upper end over which is frictionally engaged a cap 19 also formed with lateral 70 apertures. Rotation of the cap 19 relatively to the plug 18, within limits defined by the engagement of the ends of a notch 20 formed in the 75 lower edge of the cap with a radial pin 21 secured

in the plug (see Fig. 1), will vary the extent to which the apertures formed in the cap and plug, respectively, are brought into or out of register.

Gas is supplied to the passage 3 in the rib 2 of the sole 1 through a pipe or tube 22 engaged at its lower end in an inclined aperture 23 formed in the rib 2 adjacent its rear end, said pipe or tube extending parallel with the front wall of a chimney 24 of substantial height which is detachably engaged over an upstanding rim 24a, formed integrally with the rear end of a cover 25 secured over the sole 1.

The space between the cover 25 and sole 1 constitutes the combustion chamber of the iron and the lower edge 26 of the cover is adapted to rest directly on the raised periphery 1a of the sole at its rear end while being spaced therefrom by a small amount at its front end so that the only access for secondary air to the combustion chamber is through the narrow slot 27 (refer also to the construction of iron shown in Fig. 5) thus left between the front portion of the lower edge of the cover 25 and the sole 1.

As will be seen from Fig. 3, the burner pipe 7 is disposed with its medial plane somewhat above the edge 26 of the cover 25 and with its outer surface closely adjacent the inner surface of the said cover; so that the secondary air is caused to flow through the slot 27, in the direction indicated by the arrows, beneath the burner pipe 7 to the flame jets issuing from the apertures 9 in the pipe while being precluded from flowing directly to the chimney 24 under the action of the draught produced by the latter.

The chimney 24 is of rectangular cross-section 35 and its front wall extends substantially parallel with the rearwardly and upwardly inclined rear portion of a handle bow 28 which is secured to the cover 25 and sole 1 by means of a bolt 29 and also by means of the plug 18 already referred to, suitable spacers 30 being interposed between the cover 25 and the upper portion of the rib 2 on the sole 1. Such spacers 30 may be constituted by bosses cast on the rib 2 if desired, as will be understood.

A suitable handgrip 31, of wood or other heat-insulating material, is secured between the upper ends of the handle bow 28, which ends are connected by a bolt 32 (Fig. 1) passing through the handgrip, and the gas pipe or tube 22 is provided at its upper end with a suitable rearwardly directed nipple 33 for the connection of a flexible gas supply tube thereto.

As will be seen from Figs. 2 and 4, the chimney 24 is formed with a side wall 34 disposed in a vertical plane and of substantial height and a side wall 34a also disposed in a vertical plane but of small height, the upper ends of these walls being connected by a top wall constituted by a relatively short upwardly directed portion 35 connected to the wall 34 and a relatively long more steeply inclined portion 35a connected to the wall 34a.

Apertures 36 are formed in the shorter top wall portion 35 of the chimney 24 to allow of the escape of the products of combustion therefrom, the steeply inclined wall portion 35a acting as a deflecting surface and the apertures being disposed so that the hot gases are directed away from the handle 28, 31 and therefore the hand employed to operate the iron. In the case where the iron is to be employed by a right-handed person the chimney 24 would be engaged over the rim 24a on the cover 25 in such a manner that the apertured wall portion 35 would be disposed 75

(as shown) to the right of the handle, considered in the direction of the nose of the sole 1 in the plan view of Fig. 2. For left-handed persons the chimney 24 would be engaged over the rim 5 24a in the reverse manner, as will be understood.

In order that the sole 1 of the iron may be kept automatically at a desired predetermined temperature, a thermostat is provided adjacent the sole and adapted to control the supply of gas to the nozzle 11.

This thermostat comprises a rod 37 of a metal or alloy having a high coefficient of expansion, for example, magnesium or duralumin, disposed axially of the bore or passage 3 in the rib 2 of the sole 1 and coacting at its inner end with the nozzle 11. At its outer end the rod 37 is secured in a threaded plug 39 which is threadedly engaged in the internally threaded aperture of a second plug 40 engaged in the threaded end of 15 the bore 3. A packing ring 41 is interposed between the head of the plug 40 and the end of the rib 2 and a similar packing ring 42 is arranged around the plug 39 between the base of a threaded counterbore therein and the inner 20 conically countersunk end of an externally threaded collar 43 adapted to be screwed into said counterbore.

It will be seen that the plug 39 may be screwed in or out of the plug 40 for varying the extent 30 to which the inner end of the rod 37 projects into the flared inlet of the nozzle 11 without danger of gas leakage occurring.

As indicated in Fig. 4, it is preferred to provide a suitable scale of temperatures on the rear 35 wall of the cover 25 and to form the head of the plug 39 with a suitable pointer or indicator for co-operating with said scale, so that when the pointer is set to a particular temperature on the scale the thermostat is also set to reduce the supply of gas to the nozzle whenever this temperature is exceeded in the sole 1 of the iron.

It will be understood that expansion of the rod 37 causes the inner end thereof to enter further into the nozzle 11 and thus reduce the effective 45 area of the passage available for the gas flowing to the outlet 14 with a consequent reduction of the quantity of gas delivered to the burner pipe in a unit of time.

The provision of the primary air inlet apertures below the level of the top of the chimney 24 ensures that no combustion products are sucked through said apertures and the fact that the control of the supply of gas by the thermostat is effected within the nozzle 11 ensures that 55 the gas stream directed across the mixing chamber will always have the cylindrical form most advantageous for entraining primary air.

38, see Fig. 1, indicates apertures provided in the front end of the cover 25 to facilitate ignition 60 of the gas jets issuing from the burner pipe 1.

Referring now to Figs. 5 to 7, in which parts corresponding to those already described are indicated by like reference numerals, the sole 1 is 65 here again formed with the raised periphery 1a. A raised portion 2 is formed substantially centrally of the sole 1 to add to the weight thereof and the cover 25 carrying the chimney 24 is secured in place, together with the handle bow 70 28, by means of bolts 29 screwed into said raised portion 2.

The cover 25 is constructed in the manner already described to leave a secondary air inlet slot 27 but the burner pipe, while being disposed 75 substantially in the same manner as the pipe 1

shown in Figs. 1 to 4, is here constituted by a loop 44 fed from a short tube 45 disposed at the rear of the iron and bent upwardly to engage over an axial tubular extension 46 on the lower end of a cylindrical member 47.

As will be seen from Fig. 5, this member 47 is bored axially from its upper end to provide a mixing chamber 48 into which primary air is adapted to be drawn through lateral apertures 49 due to the projection of a gas stream axially 10 of said chamber from a nozzle 50 screwed into the lower end of a plug-cock casing 51 which is in turn screwed into the upper end of the bore in the member 47.

The gas stream is directed into the outwardly 15 flared upper end of a conically widening passage 52 which extends from the base of the mixing chamber 48 axially of the extension 46 on the member 47 to open into the tube 45. It is preferred to secure the latter on the extension 46 20 by means of a set screw 53 adapted to serve at the same time as a stop for a screwed sleeve 54 capable of being adjusted longitudinally on the member 47 for covering more or less of the apertures 49 for the inlet of primary air.

At its upper end the plug-cock casing 51 has secured therein a nipple 55 adapted to have the end of a flexible gas supply tube engaged thereover and the passage of the gas from said nipple 25 to the nozzle 50 is controlled by the plug-cock 56. 30

In order that the quantity of gas being burnt in the combustion chamber of the iron may readily be reduced from that corresponding to normal requirements to that which is merely sufficient to maintain the sole 1 at the required temperature 35 when the iron is on a stand or the like or when dry or slightly moist fabrics are being ironed, the gas outlet passage leading from the cock 56 to the nozzle 50 is made of smaller diameter than the gas inlet passage leading from the nipple 55 40 to said cock and the latter is formed with a conical through passage 57 which is of larger diameter than the gas inlet passage at the end adapted to co-operate therewith while being of approximately the same diameter as the gas outlet passage 45 at the end adapted to co-operate with this.

When the cock 56 is in a position in which the smaller end of its passage 57 registers with the gas outlet passage leading to the nozzle 50 the latter receives its full normal supply of gas but 50 when, as indicated in Fig. 7, the cock 56 is turned to a position in which the smaller end of its passage 57 is brought partially out of register with the gas outlet passage, the nozzle 50 only receives a reduced supply of gas sufficient to 55 maintain the desired temperature of the sole 1 of the iron for so long as no considerable amounts of heat are abstracted therefrom.

As indicated, it is preferred to provide adjustable stops for limiting the movements of the cock 60 56, these stops comprising screws 58 threadedly engaged in lugs 59 formed on the plug-cock casing 51 and adapted to co-operate with a radially projecting pin 60 secured in the operating head of the plug 56.

By adjustment of the screws 58 it is possible to regulate the quantities of gas delivered by the nozzle 50 for each end position of the plug-cock and the latter may then be turned rapidly from one position to the other as required it being understood that complete interruption of the gas supply is effected by means of another cock (not shown).

I claim:—

1. A gas iron comprising a sole having a central 75

longitudinal heat-retaining ridge upon its upper side, a cover having a top portion extending over and secured to said ridge, said cover having a peripheral wall projecting downwardly from said top portion, a burner tube between said peripheral cover wall and said ridge, said burner tube having a rearwardly projecting tubular gas and air admission plug, said ridge being provided with a longitudinal passage in the front end of which said gas and air admission plug is secured, said ridge being provided with a gas inlet into said passage and with an air inlet into said passage, and means within said passage for mixing the gas and air before entrance into the burner through said air and gas admission plug.

2. A structure as specified in claim 1; together with a heat-expanded rod disposed longitudinally within said passage and adjustably secured at its rear end, the front end of said rod being related with said air and gas mixing means to control the amount of gas admitted thereto according to the temperature of the iron.

3. A gas iron comprising a sole having a cen-

tral longitudinal heat-retaining ridge upon its upper side, a cover having a top portion extending over and secured to said ridge, said cover having a peripheral wall projecting downwardly from said top portion to provide a combustion chamber, at least the longitudinal portions of said peripheral wall being spaced upwardly from said sole to provide a narrow slit to admit secondary air, said cover having an outlet for products of combustion, and a gas burner in said combustion chamber having a burner tube substantially in contact with said longitudinal portions of said peripheral wall of said cover to prevent an appreciable amount of the secondary air from passing between said peripheral wall and said burner tube and short-circuiting to said outlet, said burner tube being spaced upwardly from said sole to permit said secondary air to pass under said burner tube, said burner tube having gas discharge orifices positioned to direct flame jets downwardly and inwardly through said secondary air and against said sole.

FREDERIK VILHELM BROSTROM.
